UNITED STATES PATENT OFFICE.

JOHN M. THOMPSON AND WILLIAM H. THOMPSON, OF BUFFALO, NEW YORK.

PIPE-CLEANING APPARATUS.

Application filed May 13, 1925. Serial No. 29,920.

This invention relates to apparatus or devices for use in cleaning pipes or pipe lines such as are used in connection with the conducting of sewage, water, oil or other fluids, and which apparatus or devices are adjustable for the purpose of enabling them to act upon pipes of different sizes.

The objects of this invention are to provide adjusting means of improved construction for use in connection with pipe cleaning apparatus whereby the apparatus can readily be adapted to operate on pipes of different diameters; also to improve the construction of pipe cleaning apparatus of this type in other respects hereinafter specified.

In the accompanying drawings,

Fig. 1 is a longitudinal central sectional elevation of a pipe cleaning apparatus or device provided with adjusting mechanism embodying this invention.

Fig. 2 is a similar view of the apparatus or device showing the parts thereof in different positions.

Fig. 3 is a fragmentary, transverse, sectional elevation thereof on line 3—3, Fig. 1.

The pipe cleaning device includes a frame member upon which the various parts of the apparatus are mounted. This frame member may be of any suitable or desired construction, that shown including a pair of end pieces A and A', each of which has radially extending arms a and a'. These end pieces of the frame or supporting member are connected by means of a plurality of longitudinally extending bars B, which in the construction illustrated are of angle shape, and the end portions of which are secured to the radially extending arms a, a' of the end pieces. By means of this arrangement the adjacent legs or flanges of the angle bars are arranged substantially parallel to each other. C represents a clevis or other attaching device secured to the front end piece and to which a rope or cable may be connected for drawing the device through a pipe. A supporting member of any other suitable or desired construction may, of course, be employed if desired.

A plurality of arms D are pivotally mounted on the supporting member, preferably by means of pivots d which extend through the adjacent flanges of the bars B of the supporting members, so that the outer ends of the arms D may swing outwardly from the supporting frame member to dif-

ferent distances therefrom. The outer ends of these arms are adapted to carry suitable pipe cleaning or scraping implements, such, for example, as a shoe or pipe cleaning implement E, which is adapted to engage the inner surface of the pipe to be cleaned and to remove deposits and accumulations therefrom. The shoe or cleaning implement E in the construction shown is of substantially T-shaped cross section and is provided with sharp cutting edges e adjacent to the ends thereof, and with a circumferentially extending flange e'. Each link D is preferably bifurcated at an end d' thereof and this bifurcated end of the link straddles the radially extending flange e' of the cleaning implement or shoe E and is pivotally connected thereto by means of suitable pivots e". The rear end of the cleaning implement in the particular construction shown is also connected to the frame or supporting member by means of a link f, which preferably extends parallel to the link D, so that the cleaning implement or shoe E will, during the adjustment thereof, be maintained in substantially parallel relationship to the supporting frame or member. The supporting frame described, the shoe or cleaning implement, and the parallel links connecting the frame and shoe have heretofore been used in connection with pipe cleaning apparatus and of themselves constitute no part of this invention and it will be understood that these parts are merely shown as one example of an embodiment of this invention and that any other pipe or cleaning implement may be mounted on the end of the arms D and any other form of supporting frame may be used, and other pipe cleaning devices may be mounted on the shoe E.

In order to effect the desired adjustment of the arms D relatively to the supporting or frame member, worm gears or worm gear segments G are preferably associated with the arms D and if desired these worm gear segments may be formed integral therewith as in the construction shown. These worm gear segments all mesh with a centrally arranged worm H, which is rotatably mounted in the frame or supporting member, the worm in the construction shown being formed on or secured to a longitudinal shaft h, the one end of which is journaled in the front end piece A of the supporting or frame

member and the other end of which extends through and is journaled in a portion of the rear end piece A'. The shaft h may be held against lengthwise movement in any suitable manner, for example, the worm H may abut against a projecting portion h' of the front end piece A to limit the movement of the shaft in one direction and the rear portion of the shaft may be provided with a sleeve or collar h^2 arranged adjacent to the rear end piece a' to limit the movement of the shaft in the other direction. The rear end of the shaft is preferably also provided with any suitable means adapted to be engaged by a wrench or other implement for turning the shaft, the rear end of the shaft being shown square in cross section as indicated at h^3 to engage with a suitable socket wrench, not shown.

It is obvious that by turning the shaft h , the worm H will turn and in meshing with the gear segments G, will cause the arms D to swing about their pivots d . By means of the construction described a single worm engages all of the worm gear segments of the several arms D, so that a simultaneous and equal adjustment of all of these arms is insured. The worm H is made of such pitch that after the same has been set to the desired position, it will positively hold the arms D against moving out of their adjusted position. By means of the construction described the pipe cleaning device can be readily adjusted to fit pipes of different diameters, and after the desired adjustment has been made, the arms D will be securely held in their adjusted positions. If desired the arms f may be replaced by other arms similar to the arms D and another worm may be placed on the shaft to cooperate with such arms.

We claim as our invention;

1. A pipe cleaning device having a frame

member, a cleaning member adapted to engage the inner surface of a pipe, a pair of links pivotally connected to said frame member and to said cleaning member for enabling said cleaning member to be moved to different distances from said frame member, a worm gear segment rigidly connected with a connecting link, and a worm rotatably mounted on said supporting member and meshing with said worm gear for adjusting said link to vary the distance of said cleaning member from said frame member. 45

2. A pipe cleaning device including a frame member, an arm pivotally mounted on the frame member and having a pipe cleaning implement near the outer end thereof, a worm gear segment formed integral with 50 said arm, and a worm journaled in the frame member and adapted to engage said gear segment to adjust said arm into different angular relations to said frame member. 55

3. A pipe cleaning device including a frame member having a plurality of longitudinally extending bars, arms pivoted to said bars and adapted to swing outwardly 70 relatively to said frame member, worm gear segments associated with said arms, and a worm rotatably mounted between said arms and engaging said worm gear segments to adjust all of said arms simultaneously. 75

4. A pipe cleaning device including a 80 frame member comprising end pieces, bars extending lengthwise of said device and secured to said end pieces, arms pivotally connected to said bars and adapted to swing outwardly with reference to said frame member, worm gear segments connected with said arms and a worm journaled in said end pieces and engaging said segments for adjusting said arms. 85
